SAFETY CUT-OFF DEVICE FOR GAS BURNERS

Application filed May 31, 1930. Serial No. 458,015.

This invention relates to safety cut-off devices for gas burners, particularly household cook-stove burners, and provides improvement therein.

There is a certain hazard connected with the use of gas burners. They are not infrequently accidentally extinguished, as by gusts of wind, boiling over of contents of vessels, acts of mischievous children, etc., and the escaping gas is extremely apt to result in loss of life and property.

The present invention provides an improved device for cutting off the flow of gas when the flame is accidentally extinguished. It provides means comprising a thermostat which acts relatively quickly, after extinguishment of the flame to cut-off the flow of gas; the thermostat may begin to act as soon as cooling begins irrespective of the degree of deflection of the thermostat by the heat. The invention further provides a very simple, effective and reliable device for the intended purpose.

An embodiment of the invention is illustrated in the accompanying drawing, wherein:

Fig. 1 is a view in side elevation of a cook-stove gas burner, equipped with a safety cut-off means according to the present invention.

Fig. 2 is a bottom plan view.

Fig. 3 is an enlarged detail view showing the valve in vertical section and the other parts in vertical elevation.

Fig. 4 is a horizontal sectional view (enlarged) on line IV—IV, Fig. 2 through the clutch.

Referring to said drawing, numeral 10 illustrates a gas-burner of conventional form, comprising a plurality of radiating arms, having numerous perforations through which the air and gas mixture which is burned, escapes. Gas enters the burner through a nozzle 12, and air through perforations (not shown) in mixing chamber 14.

Numeral 16 designates a cut-off valve controlling the flow of gas through nozzle 12. The usual manual valve 18 may be and preferably is arranged between the cut-off valve 16 and a gas supply pipe 20.

Numeral 22 designates a thermostat located in position to be heated by the flame from burner 10. As shown, the thermostat may be attached at one end to a bracket 24 attached to one of the arms of burner 10. The thermostat is preferably a bimetal strip composed of two metals (or alloys) 25, 26, having different coefficients of expansion.

Numeral 30 designates suitable connecting means for transmitting movements of the thermostat 22 to the cut-off valve 16. The connecting means may comprise a rod 32 and a lever 34, the rod being connected at one end to the free end 36 of thermostat 22, and at its other end to one arm 38 of lever 34. The cut-off valve 16 is preferably of the poppet type, the valve proper having a stem 40 projecting through the casing. An arm 42 of lever 34 is connected to stem 40, the stem 40 being conveniently provided at its outer end with a stirrup 44, into which a rounded portion of arm 42 fits. A spring 46 may be and preferably is provided for normally pressing the valve-proper toward its seat 48.

A means 50 is provided for opening cut-off valve 16 to admit gas to the burner 10 for starting a flame. The means 50 is conveniently an arm or handle connected to lever 34 and adapted to rock the lever and thereby lift the stem 40 to open the valve. Arm 50 and lever 34 may be connected by fastening both to a pin 52 which turns in a bracket 54.

A clutch 60 is preferably provided in the connection 30. The clutch 60 is preferably in the form of a sleeve 62, in which the rod 32 slides, and through which one end of the said rod 32 projects as indicated at 64. The sleeve 62 is carried by a shouldered stud 66, which stud is pivotally connected to arm 38 of lever 34 as indicated at 68. The stud is lightly held in position on the lever 34 by a cotter pin 70, or other suitable means, and an interposed light spring 72. The stud 66 and sleeve 62 are bored as indicated at 74, and a frictional connection is provided between the said sleeve 62 and rod 32 by means of a ball 78 or the like pressed against the rod 32 by means of a spring 80. The friction provided by the spring 80 and ball 78 is made of sufficient amount that the resistance in the

clutch 60 is slightly greater than the resistance of the spring 46 of the cut-off valve, whereby pull on the rod 32 may act through the clutch lever to lift the valve proper 5 against the closing pressure of spring 46. The ends of sleeve 62 are preferably counter-bored, as indicated at 82, to prevent dirt accumulating on the rod from wedging between the rod and sleeve, and thereby increasing the frictional resistance of the clutch.

The arm or handle 50 may be provided with a tail-piece 83, adapted to make contact with the end 64 of rod 32, and thereby force 15 the thermostat 22 into a deflected position, at the same time that the cut-off valve 16 is opened to admit gas to the burner, in starting the burner.

The stem 40 passes through an opening 84 20 in the valve casing, which is packed to prevent leakage of gas by suitable means, as a convex leather washer 86, which fits closely around the stem, and is pressed against the inner face of the casing by means of a light 25 spring 88 surrounding the stem and bearing against the underside of the valve proper. To prevent escape of gas around the valve stem 40 in the open position of the valve, the outer portion of the stem may be provided 30 with a shoulder 90 which is pressed against a seat 92 on the outside of the valve casing, by the thermostat acting through connection 30, when the burner gas jets are ignited and heat the thermostat.

35 Operation

To produce a flame at the burner, the normal gas cock 18, which is ordinarily a part of the combination, is first opened. The arm or handle 50 is then rocked to open the 40 cut-off valve 16. The part 83 when used may simultaneously force the thermostat 22 into a deflected position corresponding to a deflected position which it assumes when 45 acted upon by the heat of the flame from the burner. The arm 50 being connected to the lever 34, rocks the lever so that its end 42 lifts the valve stem 40 against the pressure of the spring 46, and hence admits gas to the nozzle 12, which gas passes through the mixing chamber 14 to the perforations in burner 50 10, whereupon it is ignited.

Where the arm or handle 50 is provided with the tail-piece 83, the arm or handle 50 is held momentarily after ignition of the gas 55 to permit the heat to deflect the thermostat; otherwise no holding is necessary, as the clutch 60 will slip on rod 32 and hold the cut-off valve lifted. The deflected thermostat, pulling on the lever 34 through rod 32, 60 holds the valve proper lifted off its seat as long as thermostat 22 continues to be heated by the burner flame.

As the burner flame varies in intensity, the thermostat 22 is deflected to different degrees. The connections 30 are so arranged

that in the position to which the thermostat 22 is deflected by a minimum flame, sufficient movement is imparted to the valve stem 40 to lift the valve proper sufficiently from its seat to enable the necessary amount of gas to pass to maintain the flame. With a greater intensity of flame, the thermostat 22 undergoes greater deflection. This greater deflection pulls upon the rod 32, and the clutch 60 allows the rod to slide forward in the said sleeve 62. The deflection of the thermostat 22 by the minimum flame also acts through the connection 30 to press the shoulder 90 against seat 92, and thereby limit the movement of the lever 34, and also close the opening in the casing around valve-stem 40, thereby amplifying the packing washer 86 in preventing escape of gas from the cut-off valve casing around the said stem 40.

Should the burner flame be extinguished through any cause (as a draft, boiling over of contents of cooking vessels, or the like), the thermostat 22 will quickly cool, and the thrust of the rod 32 will rock the lever 34, and seat the valve-proper, assisted by the spring 46. A comparatively slight drop of temperature of the thermostat 22 on cooling, suffices to move the cut-off valve to closing position. This drop of temperature corresponds to the relatively small rise of temperature of the thermostat caused by the heat of a flame of minimum intensity, which acts, as heretofore described, to move the cut-off valve to open position. After the cut-off valve has been closed by the initial movement of the thermostat on cooling, the push on rod 32 occasioned by further cooling of the thermostat pushes the said rod through the clutch 60, and the rod 32 continues to slide through the clutch (against the frictional resistance thereof against the rod 30), until the thermostat 22 resumes its normal position corresponding to the temperature of the room. It will therefore be seen that the arrangement is such that a small rise in temperature, corresponding to the heat imparted to the thermostat by a minimum flame, suffices to hold the cut-off valve 16 open, and that irrespective of the amount of deflection of the thermostat 22 by flames of any intensity above the minimum, that the thermostat, immediately upon extinguishment of the flame begins to act to close the cut-off valve, and effects closure upon cooling through a relatively small number of degrees, and throughout the remainder of its cooling the rod 32 connected thereto slips through the clutch 60, exerting a force meanwhile through the lever 34 in a direction to maintain the cut-off valve closed.

The location of the arm or handle 50 between the cut-off valve 16 and the usual cock 18, renders the said handle 50 inconspicuous and not noticeable to a child who may mischievously open the cock 18, and thereby provides a safeguard against a child

mischievously playing with the gas burner.

The invention may receive various other embodiments than that herein specifically illustrated and described.

5 What is claimed is:

1. A safety cut-off device for gas burners, comprising a gas cut-off valve, a thermostat, and connections between said thermostat and cut-off valve, wherein said connections

10 comprise a rod attached to said thermostat and a sleeve having a limited to and fro movement, said rod being slideable in said sleeve and said sleeve having a spring-pressed part therein adapted to bear on said rod and im-

15 positively grip the rod, whereby said rod may slide in said sleeve against the action of said spring-pressed part under the action of said thermostat after said sleeve reaches a limit of its movement, substantially as and for the

20 purpose described.

2. A safety cut-off device for gas burners, comprising a gas cut-off valve, a thermostat, and connections between said thermostat and cut-off valve, wherein said connections

25 comprise a rod attached to said thermostat, a lever connected to said cut-off valve and having a limited arc of movement, and a sleeve having a swivel connection to an arm of said lever, said rod being slideable in said sleeve

30 and said sleeve having a spring-pressed part therein adapted to bear on said rod and im- positively grip the rod, whereby said rod may slide in said sleeve against the action of said spring-pressed part under the action of said

35 thermostat after said sleeve reaches a limit of its movement, substantially as and for the purpose described.

3. A safety cut-off device according to claim 1, wherein said sleeve has an enlarged 40 internal diameter at its ends, which ends overhang the adjacent portions of the rod and prevent an accumulation of dirt on said portions of the rod and thereby inhibit sticking of the rod in the sleeve.

45 In witness whereof, we have hereunto signed our names.

ALTON LUNDIUS.
OTTO DIETRICHSON.
